ADJUSTABLE TOP-ROLL SADDLE.

1,186,066.

Specification of Letters Patent.

Patented June 6, 1916.

Application filed June 18, 1914. Serial No. 845,843.

To all whom it may concern:

Be it known that I, LEIGH S. BACHE, a citizen of the United States, and a resident of Boundbrook, in the county of Somerset 5 and State of New Jersey, have invented certain new and useful Improvements in Adjustable Top-Roll Saddles, of which the following is a full, clear, and exact description, whereby any one skilled in the art may make 10 and use the same.

The invention relates to what is commonly known as a top roll saddle which is used to hold the top rolls of a spinning frame in contact with the drawing rolls.

15 The invention relates more specifically to a saddle formed in one piece and so formed and arranged as to its component parts that it may be adjusted to the top rolls whether the full number or a complement of the full 20 number of rolls is employed. Many devices of this general character have been employed and various forms of lubricating devices have been used to provide a saddle which, while in contact with its rolls, 25 would give great efficiency through receiving lubrication. Ordinarily, such saddles are formed in two parts, with a bottom saddle part resting on the back rolls and with a forward saddle part resting on the forward 30 roll, with various types of adjustments for securing a proper tension upon the several rolls.

It has also been a common practice to 35 utilize a saddle part for the back rolls adjustable with reference to the saddle part of the front roll so that one of the back rolls might be under tension with the front roll. Such devices have of necessity required delicate relative adjustments and provision for 40 lubrication and when made in several parts, are liable to be displaced when re-setting a frame. Ordinarily in the use of a machine, the operator must use great care to properly 45 re-assemble the various parts as a reversal of position of one saddle part with reference to the other would materially interfere with the proper drawing of the yarn.

It is one of the principal objects of the 50 present invention to provide a saddle in a single structure which will provide perfect lubrication and which may be adjusted to the full number of rolls or any desired number thereof.

It is a further object of the invention to

provide a means of adjusting the tension 55 relatively to the saddle and the several rolls so that as the saddle is used on the full complement or on any number of the rolls, the desired tension may be provided.

Referring to the drawings: Figure 1 is a 60 side view of the saddle and appurtenant parts showing a set of three rolls in the ordinary position to be tensioned. Fig. 2 is a similar view with the center roll "dropped out." Fig. 3 is a similar view to that of 65 Figs. 1 and 2 with the rearmost back roll "dropped out." Fig. 4 is a perspective view of the saddle.

The invention herein described relates to 70 the saddle as a whole and contemplates the use of a single piece of material so formed and treated that it may be utilized with any combination of rolls and with features of adjustability as to tension which will permit its use whether two, three or more rolls are 75 employed. As illustrated herein, the saddle is shown as applicable to the ordinary gang of three rolls although it is apparent that its form and structure might be varied so that it might be made fully adjustable to a 80 greater number of rolls if so desired.

In the accompanying drawings 1 represents the head roll and 2 and 3 represent the back rolls of a spinning frame which bear upon the coöperating rolls 4, 5, 6 which are 85 commonly employed for spinning a "staple" of various characters.

As is well understood in this art, the top rolls 1, 2 and 3 have a relative movement with reference to the rolls 4, 5 and 6 and in 90 order to provide a proper tension effect upon the "staple" which is passed between the rolls, a saddle is employed which bears upon the rolls 1, 2 and 3 and exerts a tension effect with reference to them and their 95 coöperating rolls 4, 5 and 6.

As illustrated in the drawings, the saddle 100 consists of a single piece member 7 which is provided with a series of bearing surfaces 8, 9, 10, 11, 12, all of which are effective for various positions of adjustment of a saddle. For instance, as illustrated in Fig. 1, the head roll 1 is engaged by the bearing surface 8, while the forward back roll 2 is in engagement with the surface 10 and the rearmost back roll 3 is in engagement with the bearing surface 11. 105

In Fig. 2, the surface 9 engages the roll

1. The roll 2 is out of engagement with the saddle and the bearing surface 12 rests upon the bearing surface of the roll 3.

5 In Fig. 3 the bearing surface 10 controls the roll 1. The bearing surface 11 controls the roll 2 and the bearing surfaces 8, 9 and 12 are inactive.

Upon the upper surface of the saddle 7 are arranged a series of notches 13, 14, 15 10 which are suitably arranged to be engaged by a stirrup 16 having a suitable weight or other tensioning device for producing a tension of the saddle with reference to the top rolls. This stirrup 16 may be of any desired 15 form and the stirrup notches may be arranged in any desired manner, though ordinarily they are spaced at a proper distance to give a proper proportional tension for the rolls in whatever sequence or combination 20 they are employed.

As illustrated in the drawings, there are three bearing surfaces 8, 9 and 10 provided for the head roll and there are two bearing surfaces 11 and 12 provided for the back 25 rolls 2 and 3. With this arrangement of bearing surfaces, it is apparent at a moment's reference to Figs. 1, 2 and 3 that either of the back rolls may be dropped out and the remaining back roll utilized with 30 reference to the head roll or both back rolls may be employed with the head roll by merely shifting the single piece saddle block 7 and readjusting the stirrup 16 into one of the saddle notches or grooves 13, 14 or 15.

35 It is to be understood that the saddle might be formed of any desired material or of any composite material so long as it has the relative arrangement of bearing surfaces which will properly locate and index the 40 saddle with reference to the several rolls being employed.

In the event of metal being employed for a saddle, it is quite as obvious that some provision must be made for lubrication but an 45 applied lubricant of any form is liable to run too freely, to gum or to create a gudgeon which is liable to soil the goods.

It is preferred to avoid the liability of 50 soiling by utilizing a material which will be characteristically and inherently a lubricating material. To effect such a desirable result, it is preferred to employ a wood or fiber of analogous nature which has been saturated and made a homogeneous body of lubricant with a sufficient resistant characteristic to give strength and durability under wearing conditions. Very excellent results have been attained in a saddle of the character herein defined by impregnating a wood 55 fiber through and through with wax and hydro-carbons under a method fully described in my issue Patents Nos. 1,076,941 and 1,077,252, issued respectively under dates of October 28, 1913 and Nov. 4th, 1913. 60 There has also been employed a fiber satu-

rated with waxes and impregnated through and through with graphite. The latter form gives practically a metallic saddle having unusual features of lubrication and of an absolutely homogeneous nature. The coefficient of expansion of all parts of the saddle are substantially uniform. A saddle so formed is so completely a lubricating member that there is comparatively no heating at any of the bearing points and what little 75 heat is developed is dissipated without any deleterious effects on any particular part of the saddle structure.

It follows that there are no appreciable changes from expansion due to heating and 80 cooling and therefore the fixed bearing points of the saddle remain what is in effect an absolute constant. Thus, the fixed adjustments for the bearing surfaces with different combinations of rolls and the adjustments of the tension weights will always 85 provide an exact and perfect adjustment for securing the proper operation of the head and back rolls.

It will be noted that the single piece saddle as illustrated is provided with five bearing surfaces for the three rolls and therefore any combination of adjustment may be effected by shifting the saddle with reference to the several rolls. It is of course apparent also that the stirrup or tension device must be shifted into proper position to give the requisite equalization and distribution 90 of tension on the rolls dependent upon the special combination of rolls which is being used.

It is apparent that the invention is not strictly limited to the fiber impregnated with a lubricant in so far as the arrangement of bearing surfaces is concerned, although it is preferred, in order to secure the best results, to utilize an impregnated material which will be self-lubricating. Such a material as referred to eliminates all liability of throwing of oil such as ordinarily 110 tends to soil the goods. This is particularly true in spinning mills located in the semi-torrid zones where not infrequently a temperature of 100° or more throughout the mill is a common occurrence. Naturally, with high temperatures of this character, it is most difficult to provide a lubricant which will act efficiently under the high temperatures of summer and the comparatively lower temperatures of winter. Unless the 115 greatest care and the most unusual skill is employed by the operatives, it is impossible to prevent soiling of the goods. The oil employed for lubrication will in time work back upon the rolls and even if the goods are 120 not immediately soiled, the roll coverings must be renewed in order to prevent soiling.

Where the two piece saddle is employed, so constructed that it must be oiled, it is practically impossible for the operative to 125 130

shift the machine and transpose the rolls from one combination to another without soiling said rolls and incidentally spoiling the goods which are run therethrough.

5 The impregnation of the wood or fiber with graphite and waxes is not specifically claimed herein as this relates to a process forming the subject matter of a separate application.

10 What I claim as my invention and desire to secure by Letters Patent is:

1. A saddle block formed in a single piece and provided with a plurality of bearing surfaces for the head roll and bearing surfaces for the back rolls, said bearing surfaces spaced to provide, upon longitudinal shifting of the saddle, operative bearing surfaces for the saddle with reference to the head roll and either of the back rolls 20 with one of the bearing surfaces adjusted upon the head roll.

2. A saddle block formed in a single piece and provided with a plurality of bearing surfaces for the head roll and bearing surfaces for the back rolls, said bearing surfaces spaced to provide, upon longitudinal shifting of the saddle, operative bearing surfaces for the saddle with reference to the head roll and either of the back rolls with 30 one of the bearing surfaces adjusted upon the head roll and means for adjusting a stirrup and tension device with reference to the saddle as adjusted.

3. A single piece saddle having a plurality of bearing surfaces for the head roll and bearing surfaces for the back rolls and intermediate relief portion in the saddle for free-

ing one of the back rolls as said saddle is longitudinally adjusted across the axis of said rolls.

4. A single piece saddle having a plurality of bearing surfaces for the head roll and bearing surfaces for the back rolls arranged in sequence along the under side of the saddle and intermediate relief portion in the saddle for freeing one of the back rolls as said saddle is adjusted with reference to said rolls, and means for adjusting a stirrup and tension with reference to the saddle.

5. A single piece saddle formed from a homogeneous self lubricating material provided with a plurality of bearing surfaces spaced for adjustment with reference to the head roll and having bearing surfaces for the back rolls, the adjustment of the bearing surfaces of the saddle with reference to the head roll determining the bearing of said saddle with reference to either of the back rolls.

6. A single piece saddle formed from a homogeneous self lubricating material provided with a plurality of bearing surfaces spaced for adjustment with reference to the head roll and having bearing surfaces for the back rolls, the adjustment of the bearing surfaces of the saddle with reference to the head roll determining the bearing of said saddle with reference to either of the back rolls and means for adjusting a stirrup and tension device with reference to the saddle.
